ADJUSTABLE DOUBLE CLOSURE FOR
CONTAINERS

James William McNeil, Tampa, Fla.

Application December 31, 1935, Serial No. 56,997

8 Claims. (Cl. 221—62)

This invention relates to containers for any solid substances capable of being poured through an opening.

It is a common commercial practice at present to use paper cartons, cans and boxes made of sheet metal, and packages made partly of paper and partly of metal or other materials as containers for salt, sugar, soda, baking powder, flour, flaked and granular cereals, spices, raisins, and many other foodstuffs and other materials of which a portion only is used at one time by the ordinary consumer. The great majority of such containers are intended to be opened only by cutting, tearing, or punching in a top or side of the package, and they have no means provided for effecting a satisfactory closure to preserve the portion not removed.

It is a primary object of the present invention to provide a simple, inexpensive, and efficient sliding closure for a preformed opening in a container, which will bear upon both an inner and an outer surface of the container around the opening whereby pressure either from the outside or from the inside will act to force the closure more tightly in place.

A further object of the invention is to provide a safe closure for containers of the types in common use for solid loose materials which will prevent leakage and deterioration of the material during shipment and while on the dealer's shelves, which can readily be opened by the consumer to permit pouring out of the desired amount in a regulated flow, and which can readily be closed again to effect a tight closure to protect the remaining portion from dirt, insects, or moisture.

Other objects of the invention are to provide a closure which will not interfere with stacking containers one upon another, which will be tight whether the package is upright or upside down, which requires no additional seal to prevent leakage or to hold it closed during shipment and handling, which is adjustable to vary the size of the pouring opening, and which is sanitary because the opening need not be touched by a tool or by the fingers of the user.

Additional advantages and objects of the invention will appear in connection with the following description of certain preferred embodiments of the invention selected as illustrative of the principles involved, it being evident that the invention is not limited to the exact details shown but is capable of many other forms of construction.

In the drawing, Figure 1 is a plan view of a hexagonal container top provided with a closure

slidable in a straight line; Fig. 2 is a bottom view of the same top; Fig. 3 is a longitudinal section through the closure member on the line III—III of Fig. 1; Fig. 4 is a transverse section on the line IV—IV of Fig. 1; Fig. 5 is a plan view of a circular container top having a closure member slideable on a curve; Fig. 6 is a bottom view of the same top; Fig. 7 is a section on the line VII—VII of Fig. 5; Fig. 8 is a section on the line VIII—VIII of Fig. 5; Fig. 9 is a plan view of a rectangular container top; Fig. 10 is a bottom view of the same top; Fig. 11 is a transverse section on the line XI—XI of Fig. 9; Fig. 12 is a longitudinal section on the line XII—XII of Fig. 9; Fig. 13 is a longitudinal section of another modification of the invention; and Fig. 14 is a plan view of a modified form of flat spring for use with a closure such as that of Fig. 1.

Referring to Figs. 1, 2, 3, and 4, inclusive, the hexagonal container 1 is shown as having a pasteboard top 2 having portions removed to form a triangular pouring opening 3 and a guide slot 4.

An outer closure strip 5 is indicated in solid lines in Fig. 1 as lying at one side of the opening 3, and is shown in broken lines as covering the opening. An inner closure strip 6 lies at one side of the opening 3 in Fig. 3 and covers the opening in Fig. 2. A flat spring 7 having its central portion bent upwardly at 8 as best shown in Fig. 3, is held under tension against the strip 5 by a thin metallic clamping member 9 which passes through openings in the strips 5 and 6 and through the slot 4 in the top 2, the ends of the clamp 9 being bent sidewise in opposite direction to lie flat against the inner surface of the inner closure strip 6 as shown in Figs. 2 and 4. The slot 4 is of a length to permit sliding movement of the closure strips 5 and 6 from the position in which the opening 3 is fully covered to a position in which it is fully open as shown in Fig. 2. The slot may serve to limit the sliding movement of the strips by contact of the clamp 9 with the ends of the slot, or the member 6 may be of a length to come in contact with the inner walls of the carton, as suggested in Fig. 2.

In Figures 5, 6, 7, and 8, the closure members 10 and 11 are connected by split rivets 12, 12, which also serve to hold the spring wire 13 in place upon the outer surface of the strip 10. The carton top 14 is shown as formed with a depression 15 in which the member 10 may slide, the depth of the depression being made such that the spring 13 will not project above the plane of the top of the container. This will be especially desirable where the top 14 is made of metal

too thick to bend down with the weight of a second package set upon the top. A slot 16 formed in the top 14 permits the sliding movement of the rivets 12 and this slot is covered at all times by 5 the members 10 and 11 throughout the range of their sliding movement which will be limited by the walls of the depression 15. The pouring opening 17 may have rounded corners as indicated in Fig. 6 instead of being cut at a sharp 10 angle as is shown for the opening 3.

In Figs. 9, 10, 11, and 12, the rectangular carton 18 has a circular pouring opening 19 near one end of the top 20, and closure members 21 and 22 are slidable longitudinally of the top 15 to open and close the opening 19. These members 21 and 22 are made of a resilient material such as celluloid, thin metal, or stiff paper, stamped or pressed upward from a flat margin 23 or 24, with centers pressed inward to lie 20 in contact with each other when assembled, a staple 25 being used to hold them together with their margins in close contact with the opposite faces of the top 20. A slot 26 acts as a guide to permit longitudinal movement while preventing 25 sidewise or angular movement of the members 21 and 22 enough to uncover the opening 19. With this arrangement, the elasticity of the material of the closure members is utilized to maintain close contact with the top, 30 and no supplemental spring is needed. While the margins 23 and 24 are preferably flat as giving a greater area of contact, it will be evident that they may be curved, or that they may consist merely of the natural thickness of the 35 edges of the material of which the members are made.

In Fig. 13, the closure members 27 and 28 are shown as merely flat strips held together by a wire fastener 29, the free ends of which may 40 extend longitudinally of the inner face of the inner strip to act as a simple form of spring to aid the natural elasticity of the strip 28.

Fig. 14 is a plan view of a spring 30 which may be used with such a sheet metal clamp as the 45 member 9 of Fig. 1. The notches 31 act to prevent the spring from slipping out from under the clamp. In this form, a simple flat spring strip requiring no die to give it special shape may be used as a resilient element instead of the 50 rounded spring member 7 of Fig. 1 or the wire spring 13 of Fig. 5.

The shape of the two closure members may be the same, so that the same blanks may be used for inner and outer members, or they may 55 be different, as where the outer member is printed or is made of a more expensive material than that of the inner member, as is indicated in Figs. 1 and 2, and in Figs. 9, 10, and 11.

The shape of the closure members may also 60 depend upon the shape of the container, as in Fig. 1, where the outer closure member is made with the front edges parallel with the sides of the container to cover the opening 3 without projecting beyond the margins of the top. Similarly, the inner member may be of a different shape 65 from the outer member, there being no need to notch the sides for easy engagement by the fingers or to give any distinctive form to the rear end, since it need only to be of an extent 70 to cover the slot while the front end serves to limit the forward movement of the closure by engaging with the sides of the carton.

Because of the resiliency of the material of 75 which the closure members are made, or because of the action of the springs bearing upon them,

the double sliding closures may be held firmly by friction at any desired point in their path of travel, enabling the user to adjust the size of the opening by leaving any portion covered to limit the size and hence the rapidity of flow to control the quantity dispensed in a given time. 5 Adjusting the members 5 and 6 of Fig. 1 over a V-shaped opening such as shown at 3 until it is almost closed, fine table salt, for example, may be sifted out in a fine stream, as contrasted with 10 the ordinary pouring spouts which permit a relatively large mass to escape, which may be far in excess of what is needed or desired, often resulting in waste.

Where a larger opening is needed, as for use 15 with flaked cereals, a wire spring such as 13 in Fig. 5 made of a size to encircle the entire opening will furnish pressure at the exact place where it is most needed, holding the margins of the closure member 10 in tight contact with the 20 surface of the carton. The member 10 may thus be of relatively light material since the resilient metallic wire will furnish all the force necessary to hold the edges in engagement with the 25 carton top.

It will be evident that many changes in details 30 of construction and arrangement of parts may be made without departure from the principles of the invention. The spring 13, shown as on the outside, could obviously be placed on the inside as are the spring ends of the wire 29 in Fig. 13. Similarly, such springs as 7, 13, and 30 may be used on both inside and outside, as are the two elastic members 21 and 22.

The matter of the foregoing description is thus 35 to be understood as merely illustrative and not in a limiting sense, since it will be clear to those familiar with the art that the same invention can be carried into effect by many other means than those shown and described, with many changes 40 in form, size, proportions, and mode of construction of parts.

I claim:

1. In combination with a container having an 45 opening in the wall thereof, two closure members mounted to slide on opposite surfaces of the container wall from a position in which the opening is completely covered on both sides to a position in which said opening is at least partly uncovered.

2. In combination with a container having an 50 opening in a wall thereof, two closure members one upon the inside and the other upon the outside of said container each adapted to cover said opening, and means connecting said closure members for simultaneous sliding movement in engagement with opposite sides of said wall from a position in which the said opening is completely covered on both surfaces to a position in which the said opening is at least partly uncovered.

3. In combination with a container having a 55 pouring opening and a guide slot formed in a wall thereof, two closure members each adapted to cover said opening and said slot, and resilient means connecting said closure members for simultaneous sliding movement on opposite surfaces of said wall, said means connecting said closure members cooperating with said slot to limit the movement of said members.

4. In combination with a container having a 60 pouring opening formed in a wall thereof, two closure members each adapted to cover said opening, means for connecting said closure members on opposite sides of said wall for simultaneous 65 sliding movement, and a spring mounted to bear upon the surface of at least one of said closure 70 members.

members to hold its margin in frictional contact with the surface of said wall.

5. In combination with a container having a pouring opening formed in a wall thereof, two closure members each adapted to cover said opening, means connecting said members for simultaneous sliding movement over and off said opening, and a resilient element engaging the margin of at least one of said members to hold it in close contact with the surface of said wall when in the closed position.

6. In combination with a container having a pouring opening formed in a wall thereof, a pair of closure members each adapted to cover the opening, means connecting said members for sliding movement on opposite faces of said wall, and a spring member encircling the pouring hole when the closure members are in closed position to press the margins on one of said members into close

20 contact with the face of the container wall.

7. In combination with a container having a pouring opening and a slot formed in a wall thereof, a pair of closure members each adapted to cover the said opening and the said slot, said members being formed with central projecting ridges adapted to meet each other within said slot, and securing means connecting said members through said ridges whereby the said ridges cooperate with the said slot to limit the movement of the closure members.

8. In combination with a container having a pouring opening formed in a wall thereof, a pair of closure members each adapted to cover the said opening, and a wire fastening member passing through the central portion of both members and having its ends bent in opposite directions to bear upon the surface of one of said members to hold both of said members under tension on said wall.

JAMES WILLIAM MCNEIL. 20
